Primary Examiner — Garth Rademaker*Assistant Examiner* — Katie Stofko Mroczka(74) *Attorney, Agent, or Firm* — McAndrews Held & Malloy, Ltd.(57) **CLAIM**

The ornamental design for an electronic device, as shown and described.

DESCRIPTION

FIG. 1 is a front perspective view of our new design for an electronic device in a first folded position;

FIG. 2 is a front view thereof;

FIG. 3 is a rear view thereof;

FIG. 4 is a left-side elevation view thereof;

FIG. 5 is a right-side elevation view thereof;

FIG. 6 is a top plan view thereof;

FIG. 7 is a bottom plan view thereof; and

FIG. 8 is a rear perspective view of the electronic device in an unfolded position;

FIG. 9 is a top plan view of the electronic device in a second folded position;

FIG. 10 is a top plan view of the electronic device in a third folded position; and,

FIG. 11 is a top plan view of the electronic device in a fourth folded position.

The evenly-spaced dashed broken lines in the drawings illustrate portions of the electronic device that form no part of the claimed design. The dot-dash broken lines in the drawings illustrate a boundary line that forms no part of the claimed design.
